UNITED STATES PATENT OFFICE.

GEORGE J. BOHLMAN, OF MEDFORD, MASSACHUSETTS.

METHOD OF MAKING PAPER CUPS.

1,181,965.

Specification of Letters Patent.

Patented May 2, 1916.

Original application filed November 2, 1914, Serial No. 869,762. Divided and this application filed February 19, 1915. Serial No. 9,260.

To all whom it may concern:

Be it known that I, GEORGE J. BOHLMAN, a citizen of the United States, residing at Medford, in the county of Middlesex and 5 State of Massachusetts, have invented an Improvement in Methods of Making Paper Cups, of which the following is a specification.

In another application Serial No. 869,762, filed November 2, 1914, of which 10 this application is a division, a paper drinking cup is shown having an improved form of rolled-edge at either or both ends of its body. A rolled-edge at the top of the cup is 15 of advantage as contrasted with the usual thin sharp edge, as it gives additional stiffness and rigidity to the cup, and also presents a smooth lip-engaging portion which will not have a tendency to cut the lip; and 20 a rolled-edge at the bottom of the cup is also of advantage, as by it a stiff flange is produced below the bottom-piece, by which to support the cup in upright position, even 25 when filled, and by which the bottom-piece is held from dropping out, so that bottom-pieces composed of flat disks may be employed.

Heretofore, paper cups have been produced having rolled edges, but, so far as I 30 am aware, the methods employed for producing the same has involved the employment of paraffin wax or some stiffening substance, which is applied to the surface of the cup-body, and which collects and hardens in the roll which is formed, thereby 35 stiffening the edge to hold it in rolled position. In making the cup of said application in a manner involving my present method, I 40 select a rather heavy stiff paper as compared with the paper usually employed for making drinking-cups, which paper contains a size or equivalent stiffening substance by which it is also rendered waterproof or 45 at least partially waterproof, and cut from it a blank, and arrange the blank on a form thereby to produce a frusto-conical or other shaped cup-body, and then apply thereto, in any suitable manner, any suitable form 50 of bottom-closure, although said bottom-closure may be applied at any other time, so far as the present process is concerned. Then the end-portion of said cup-body is heated to a high temperature and is bent 55 to form a roll and then the cup-body is al-

lowed to cool, whereupon the roll thus 55 formed, becomes permanently set.

One way of carrying out my invention is here shown which consists in holding the cup-body stationary, with that end-portion which is to be rolled in engagement with a 60 rapidly-revolving heating and bending device, thereby heating the same by its frictional engagement therewith, and when heated or while it is being heated, applying pressure in a longitudinal direction upon it, 65 such for instance as the pressure of the hand, which is sufficient to cause its end-portion to follow the curvature of the heating and bending device, thereby to form the roll, and then removing the cup-body from the 70 heating and bending-device and permitting it to cool, whereupon the rolled edge becomes permanently set. The apparatus involving a heating and bending-device which may be employed for this purpose forms the 75 subject matter of an application Serial No. 869,764, filed November 2, 1914.

In so far as the method herein described of rolling the edges or end-portions of the cup-body, either or both end-portions of 80 the cup-body may be rolled, the upper end-portion being rolled outward, and the lower end-portion being rolled inward. The outwardly rolled edge is slightly stretched while it is being bent, which stretching is 85 permitted while the paper is at a high temperature, probably on account of the softening of the sizing which is contained in the paper. On account of the paper which I prefer to employ in forming the cup, 90 being substantially waterproof, further waterproofing need not be resorted to, but if desired, the cup may be coated with paraffin wax in any well-known manner. The cup-body including its rolled edge is resilient, 95 which admits of its being withdrawn from a holder.

The method herein involved may be practised on other paper and other forms of receptacles as for instance, a cup-body may 100 be made of paper in a well-known manner, and then coated with paraffin wax to render it waterproof, and then allowed to cool, and then the waterproofed cup-body may be heated or at least its end-portion, and while 105 heated, its edge may be rolled, and subsequently allowed to cool, whereupon it becomes permanently set.

Figure 1, is a side elevation and partial vertical section of a paper cup, having its upper end rolled outward. Fig. 2, is a similar view of a paper cup, having its upper and lower ends rolled, one outward, and the other inward. Fig. 3, is a detail view of a heating and bending device which may be employed in rolling the end-portions of the cup-body, and Fig. 4, is a similar view illustrating one end-portion of the cup-body with its end-portion rolled.

Referring to Fig. 1, 1 represents the cup-body here shown as frusto-conical, and 2 the bottom-closure arranged in and adapted to close one end thereof. In this form of cup, the upper edge is rolled outward.

Referring to Fig. 2, 1 represents the cup-body here shown as frusto-conical, and 3 the bottom-closure, which is represented as a disk, and in this form of cup both ends of the cup-body are formed with rolled edges, the upper edge being rolled outward and the lower edge being rolled inward, the rolled edge at the bottom serving to hold the bottom-piece 3 in place, or at least from falling out.

Referring to Fig. 3, 10, represents a circular-member having a centrally disposed projecting portion 12 of frusto-conical form, and having a groove 13 arranged on the top of said member at the base of said projecting-portion. Said member is arranged on a spindle 15 bearing a belt-pulley 16, over which a belt 17 passes, by which to rapidly revolve said member. Said member constitutes the heating and bending-device for heating and bending one end of the cup-body, and it will be understood that the other end of the cup-body will or may be bent or rolled in a similar manner. The dimensions of the frusto-conical projecting-portion 12, are materially less than the corresponding dimensions of the cup-body, except at the base, which latter corresponds with the diameter of the cup-body, and a loose fit is thereby obtained, yet said projecting-portion will amply support the cup-body when the latter is placed thereon, pro-

viding it is held by the fingers or other means, and also will serve as a guide to direct downward movement of the cup-body when placed thereon, and pressure in a downward or longitudinal direction is applied to it, say for instance, the pressure of the hand.

To roll the edge, the cup-body is placed on the rapidly revolving member, and its edge to be rolled is caused to enter the groove 13, and thus frictionally engage the member 10, and while the cup-body is held stationary and the member 10 is revolving, said end-portion, which is in engagement therewith, is heated to a high temperature, care being taken not to scorch the paper, and while thus heated, pressure is applied to the cup-body in a downward or longitudinal direction, and said heated end-portion is caused to follow the curved wall of the groove 13, being expanded or stretched and rolled as represented in Fig. 4. The cup-body is then removed from the heating and bending-device, and is allowed to cool, whereupon its rolled edge becomes permanently set. The roll may be formed as a complete circle as shown in Fig. 4, but by removing the cup-body from the heating and bending-device before the roll has been thus formed, the roll will comprise a portion only of a circle.

I claim:—

The method herein described of forming a rolled edge on the end-portion of a paper cup-body, which consists in heating the end-portion of the cup-body to a high temperature, and bending and simultaneously stretching said end-portion while so heated, to form an outwardly extended roll, and then allowing the cup-body to cool, whereupon the roll becomes permanently set.

In testimony whereof, I have signed my name to this specification in the presence of two subscribing witnesses.

GEORGE J. BOHLMAN.
